FRANKLIN S. SMITH, OF BROOKLYN, NEW YORK, ASSIGNOR TO PRODUCTS PROTECTION CORPORATION, A CORPORATION OF DELAWARE.

X-RAY APPARATUS.

Application filed December 8, 1926. Serial No. 153,281.

This invention relates to X-ray apparatus and systems and more particularly to X-ray apparatus adapted to operate at very high potentials.

One of the objects of this invention is to provide an X-ray apparatus and system which will be of simple and thoroughly practical construction and arrangement and capable of highly efficient action when in use. Another object is to provide apparatus of the above character in which a high voltage X-ray tube may be dependably and reliably operated while at the same time the achievement in a simple and thoroughly effective manner of the safeguarding of auxiliary apparatus against such high voltage is brought about. Another object is to provide an X-ray system and apparatus in which, while the initial source of potential is an alternating one, the X-ray tube may be operated with a uni-directional high potential and hence with a uni-directional current, but without endangering or over-stressing the rectifying device employed. Another object of this invention is to provide a system of the above-mentioned character in which a single rectifying thermionic valve may be safely employed in conjunction with a plurality of appropriate condensers, but without subjecting such a valve to either the full potential applied to the X-ray tube itself or the total potential across the condensers. Another object is to provide an apparatus and system of the above-mentioned type which will be well adapted to meet the varying conditions of hard practical use. Other objects will be in part obvious or in part pointed out hereinafter.

The invention accordingly consists in the features of construction, combinations of elements and arrangements of parts as will be exemplified in the structure to be herein-after described and the scope of the application of which will be indicated in the following claims.

In the accompanying drawings in which are shown several of various possible embodiments of certain features of my invention,

Figure 1 is a diagrammatic representation of the circuits and apparatus of a preferred embodiment of my invention, certain mechanical features being shown in elevation;

Figure 2 is a plan view as seen from the right of Fig. 1, showing the mechanical

features of the high tension switch 28-23-29 of Fig. 1, and

Figure 3 is a sectional view as seen along the line 3-3 of Fig. 2.

Similar reference characters refer to similar parts throughout the several views of the drawings.

As conducive to a clearer understanding of certain features of this invention, it may at this point be noted that in certain uses of the X-ray tube the characteristics of the latter when operated at very high potentials are desired to be made use of; while X-ray tubes can be made to operate under and to withstand relatively high potentials, in order to achieve in practice the advantages of such characteristics of the X-ray tube, yet the application of such relatively high potentials to the tube gives rise to certain serious difficulties and disadvantages in the apparatus associated with the X-ray tube and by or through which it is energized at this high potential. Such of these advantageous characteristics of the X-ray tube as above outlined may be conveniently made of practical use where the X-ray tube is connected so that its immediate source of energy comprises two condensers connected in series, one of which is charged during the half cycle of an appropriate high tension alternating current and the next one is charged at the succeeding half cycle of the same high potential current. An advantage of such an arrangement resides in the fact that the condensers thus, in series, provide an appropriate high tension for energizing the X-ray tube while, for charging the condensers, and individually, a potential substantially only half of that normally applied to the X-ray tube need be employed. Such an arrangement is usually carried out in practice by the employment of uni-directional valves, conveniently of the hot cathode or thermionic type, for example; these valves insure the charging of the respective condensers during the appropriate half cycles of the alternating potential applied thereto and, being uni-directional, also insure against the discharge of one condenser while the other is being charged.

But such a circuit arrangement, while achieving a number of desirable advantages has the very serious disadvantage that the rectifying or uni-directional valves become subjected to the full potential applied to the

X-ray tube and either the potential applied to the X-ray tube must be therefore and necessarily limited to one which the rectifying valves themselves can withstand and thus the desired characteristics of the X-ray tube become unattainable, or the rectifying valves become over-stressed, rapidly and quickly break down, and thus destroyed. A dominant aim of this invention is to provide an X-ray system and apparatus in which fullest advantage of the characteristics of a very high potential X-ray tube may be taken while at the same time eliminating in a thoroughly practical way such defects, limitations and disadvantages as have just been pointed out, and to carry out this aim by utilizing only a single rectifying valve.

Referring now to the drawing and more particularly to Figure 1, there is shown at 10 an X-ray tube having a cathode 11 conveniently of the filament type and an appropriate anode 12 for coaction therewith; the cathode 11 may be supplied with heating current through any appropriate source as, for example, by means of a suitable transformer indicated generally at 13. Two suitable condensers 14 and 15 are connected in series through a grounded conductor 16 and these condensers 14 and 15 are in turn connected by the conductors 17 and 18 to the cathode 11 and anode 12 respectively of the X-ray tube 10. If, therefore, each condenser is individually charged from an appropriate source, the potential applied to the X-ray tube 10 will be substantially the sum of the potentials across the charged condensers.

The condensers 14 and 15 are arranged to be successively charged from preferably the same source of potential, and the latter takes the form of a step-up transformer having a primary winding 19 and a secondary winding 20, one terminal of which is connected to the conductor 16 which connects the condensers 14 and 15 in series; this terminal of the winding 20 may be grounded as at G. The transformer 19-20 is of such a ratio of transformation that the potential across the secondary winding 20 is appropriate for suitably charging each of the condensers 14 and 15; the primary winding 19 may be energized from any suitable source of alternating potential.

Associated with the above described apparatus is a synchronously driven switching mechanism generally indicated at 21, together with a uni-lateral valve or kenotron generally indicated at 22. This synchronously operated switching mechanism 21 preferably comprises two electrodes 23 and 24 connected to a synchronous motor 25 through the shafts 26 and 27 respectively, the latter being suitably insulated or preferably of an insulating material so as to isolate the synchronous motor 25 from the conductive parts of the switching mechanism.

The electrode 23 is preferably of a generally cylindrical shape with curved or sphere-like ends, as is also the case with the electrode 24. Electrode 23 is provided with a conductive blade 23^a, conveniently formed integrally therewith, and of such a length that it just clears the fixed terminals or electrodes 28 and 29, spaced 180° from one another in the plane of rotation of the blade 23^a. The electrodes 28 and 29 are preferably spherical. The blade 23^a is shaped so as to provide an arcuate end portion (see Fig. 2) of an extent in the direction of the plane of rotation thereof sufficient to insure the closure of the associated high tension circuit for a sufficient length of time. Moreover, the coacting electrodes 28 and 29, being preferably spherical, together with the blade 23^a provide circuit controlling members well adapted to insure a proper duration of the arcing over of the high tension current and moreover in a manner relatively noiselessly. But in order further to diminish the noise of the apparatus, the conductive blade 23^a is, in cross-section, and as will be more clearly seen from Figure 3, given a stream-line shape effective to reduce to a minimum the air disturbances due to the speed of rotation of the blade 23^a and thus likewise to reduce the resultant noise.

The rotatable electrode 24 is provided with a like blade 24^a adapted to coact with the fixed terminals or electrodes 30 and 31 likewise spaced 180° in the plane of rotation of the blade 24^a and adapted to coact therewith in a manner substantially similar to the coaction of the blade 23^a with its associated electrodes 28 and 29. The rotatable blades 23^a and 24^a, however, are spaced, with respect to their axis of rotation in the particular arrangement illustratively shown in the drawing, 180° from one another.

Electrode 24 and hence blade 24^a, connected by conductor 34 to one electrode, namely, the plate 33 of the rectifying valve 22 and the electrode 23 and hence the blade 23^a is connected by conductor 32 to the other electrode, namely, the cathode or filament 35 of the kenotron 22. The rectifying valve 22 is preferably of the thermionic type and its cathode 35, taking the form of a filament, may be heated from any suitable source such as a transformer generally indicated at 36.

Electrode 29 is connected by conductor 37 to one terminal of condenser 14; electrode 31 is connected by conductor 38 to one terminal of condenser 15. Electrode 28 is connected by conductor 39 to the free terminal of the secondary winding 20 of the step-up transformer 19-20 and to this same terminal of the winding 20 electrode 30 is connected by conductor 40.

In the operation of the apparatus and system, the blades 23^a and 24^a of the switching mechanism 21 are driven synchronously by

the synchronous motor 25, the various parts being so related that, at the peak of the potential of each half cycle, the blades 23^a and 24^a will be in coacting position with one of the fixed electrodes and will hence be in circuit closing relation. With the apparatus in the position shown in Figure 1, the condenser 14 receives a charge at the peak of the potential of one half cycle of the energy output of the secondary winding 20 of the transformer 19—20. Bearing in mind that the blades 23^a and 24^a are rotating, the arcuate end portion of each blade (as is more clearly seen in Fig. 2 with respect to the blade 23^a) permits this charging circuit to remain closed for a sufficient length of time to permit the condenser 14 to receive an adequate charge, and this occurs throughout an appropriate portion of the peak of the potential half wave active at the time. The potential of the condenser 14 is thus raised, on being charged, to one that is commensurate with if not entirely equal to the potential across the secondary winding 20 of the transformer 19—20.

The charging circuit thus effective will be seen to be substantially as follows, and the electron flow of charging current therein will be in the direction in which the said charging circuit is traced:—from one terminal of the secondary winding 20, conductor 16, condenser 14, conductor 37, switch electrode 29, rotatable switch members 23—23^a, conductor 32, cathode 35 of the unilateral valve or kenotron 22, anode 33, conductor 34, rotatable switch members 24—24^a, switch electrode 30, conductor 40, and thus back to the other terminal of the secondary winding 20. The electron flow of charging current through the condenser 14 will be seen to be in the direction in which the charging circuit has just been traced, as will be clear from the direction of the electron flow from the cathode 35 to the anode 33 of the valve 22; accordingly, the electron flow of charging current into the condenser 14 will be seen to be in the direction from the right to the left as the circuit of Fig. 1 is viewed in the drawing.

By the time that the next half cycle arrives and achieves a value of potential approaching that of the peak of this succeeding half wave, the synchronous motor 25 will have rotated the switch member 23 and 24 throughout 180°, the switch blades 23^a and 24^a being thereby removed from coacting relation with respect to electrodes 29 and 30 respectively and being positioned for coaction with the electrodes 28 and 31 respectively.

The charging circuit for the other condenser 15 is thus completed and the electron flow of charging current therein will be seen to be in the direction in which the charging circuit is traced as follows:—from

one terminal of the secondary winding 20, conductor 39, switch electrode 28, switch members 23—23^a, conductor 32, cathode 35 of the valve or kenotron 22, anode 33, conductor 34, switch members 24—24^a, switch electrode 31, conductor 38, condenser 15, conductor 16, and thus back to the other terminal of the secondary winding 20. The electron flow of charging current in this charging circuit will thus be seen to be in the direction of the electron flow of current from the cathode 35 to the anode 33 of the valve or kenotron 22, and accordingly the electron flow of charging current through the condenser 15 will be seen to be in the direction from the right to the left as the diagram of Fig. 1 is viewed in the drawing.

The cycles of operation above described are thereupon repeated, the kenotron 22 insuring the charging of each condenser in appropriate direction and preventing the discharge of a charged condenser through the transformer winding when the potential of the latter, in its cycles, decreases or reverses.

It might further be pointed out that the condensers 14 and 15 are successively charged at substantial rapidity, each being charged during one-half cycle of the alternating potential effective in the high tension winding 20 of the transformer 19—20; if it be assumed that the low tension winding 19 of the transformer is supplied with energizing current from a commercial source of alternating potential, for example, one of sixty cycles, it will further be seen that the successive and alternate charges to the condensers follow each other with great rapidity. The effect of this action is to make effective across the serially connected condensers 14 and 15, and hence across the conductors 18 and 17, a unidirectional potential of substantial constancy and substantially free from material pulsations or variations. The constancy of this unidirectional potential is further contributed to by the effect of the condensers themselves in tending to smooth out pulsations or variations. The electrodes of the X-ray tube 10 will thus have impressed upon them a unidirectional and relatively constant potential equivalent substantially to twice the potential of the high-tension winding 20 of the transformer.

While the electron flow of charging current through the condensers 14 and 15 takes place, as hereinbefore described, in the direction from the right to the left as the diagram is viewed in Fig. 1 of the drawing, the electron flow of discharge current of the condensers through the X-ray tube 10 takes place in the reverse direction and hence in a circuit that may be traced as follows, the electron flow taking place in the direction in which the circuit is traced:—condenser 130

14, conductor 16, condenser 15, conductor 17, cathode 11 of the X-ray tube 10, anode 12 and, by way of conductor 18, back to the condenser 14. The electron flow of the current which thus energizes the X-ray tube 10 will be seen to take place in the direction of the electron flow from the cathode 11 to the anode 12 of the X-ray tube 10.

But as these cycles of operation are repeated, a further and highly important action, due to certain structural features of this invention, takes place. As has hereinbefore been pointed out, the electrodes of the synchronously operated switching mechanism 21 are of predetermined shape; the fixed electrodes, for example, are substantially spherical while the main body portion of the rotatable electrodes, for example, the member 23, is generally cylindrical with rounded end portions. These conductive parts are so spaced and the radii of their various curved surfaces so chosen, that each fixed electrode, together with its associated rotatable electrode are substantially corona-less in their action and moreover, have a capacitance, when related to each other as are the members 23 and 28, for example, of Figure 1, equivalent to or preferably less than the capacity of the kenotron 22. The circuit of condenser 15, with the parts positioned as shown in Figure 1, will therefore be seen to have included in it a capacity equivalent to that of the kenotron 22 and also the capacitance between the members 23 and 28; but by reason of the relative magnitudes of these capacitances, there is avoided a voltage drop across the kenotron in this circuit which will be greater than half the voltage across these two capacitances in series. The kenotron 22 is thus safeguarded against an inverse distribution of condenser potentials of such a nature as will over-stress, and cause breakage of, the kenotron 22.

The rotatable switch member 23 with its associated switch blade 23^a will therefore be seen to constitute with a coacting fixed electrode what is in effect a variable capacitance included in the condenser charging circuits. Aside, therefore, from effecting the proper sequence insertion of the kenotron 22 in the two charging circuits of the condensers 14 and 15, the synchronous apparatus 21 will thus be seen to bring about this effect by synchronously and alternately changing the capacitance included in each condenser charging circuit from one whose value is adequate to permit the flow of charging current in the one circuit to one which is adequate not only to prevent the flow of charging current in this same circuit when the succeeding half cycle is effective, but also to so change the characteristics of the same circuit that the kenotron is effectively safeguarded against over-voltages.

By way of illustration merely, and as further conducive to a clearer understanding of certain features of this invention, it might be assumed, for example, that the limiting potential which the kenotron 22 can withstand safely is 100 kv. Each condenser 14 and 15 may thus be charged at substantially this potential so that the available potential for operating the X-ray tube 10 is approximately or substantially 200 kv. Assuming further that the condenser 15 has been charged during one half cycle and that the condenser 14 is being charged during the next half cycle, the potential across the condenser 15 will be 100 kv. (active in one direction) and the potential across the secondary winding 20 will be 100 kv. and, with respect to the charged condenser 15, active in the same direction as the potential across the latter. Across conductors 38 and 40, for example, therefore, there will be active a potential equivalent to the sum of these two potentials, namely, 200 kv. but this high potential, bearing in mind the assumption that the limiting voltage that the kenotron 22 can safely withstand is 100 kv., cannot be made effective at or upon the kenotron 22 since there is interposed in any circuit through which it attempts to be effective not only the gap between the fixed electrode 31 and the rotatable electrode 24 (as well as the gap between the fixed electrode 28 and the rotatable electrode 33) but also the capacitances of the electrodes forming these gaps. These capacitances, however, being proportioned as hereinabove noted (that is, with the parts in the position shown in Figure 1) furthermore prevent an inverse distribution of condenser potentials taking place in such a manner that the kenotron 22 becomes over-stressed. Assuming that the capacitance of the thus interposed gap or gaps in the circuit in which the cumulative potential of 200 kv. is substantially equal to the capacitance of the kenotron 22, then the cumulative potential of 200 kv. is distributed in this circuit so that a voltage of 100 kv. exists across the kenotron 22 and a voltage of 100 kv. exists across the capacitance formed by the gap electrodes. The assumption by the capacitance of the gap electrodes of a substantial portion of this cumulative potential thus prevents the kenotron 22 from being subjected to the full cumulative potential above assumed to be 200 kv.

It will thus be seen that the limiting voltage which the kenotron can safely withstand need no longer limit the potentials applied to the X-ray tube itself, and need not therefore limit the action and characteristics of the latter. Moreover, it will be seen that the many advantages of utilizing a single uni-lateral valve may be effectively achieved, and moreover, with apparatus not

only of effective safeguarding action but also capable of rugged and inexpensive construction. It will therefore be seen that there has been provided in this invention a system and apparatus in which the several objects hereinbefore noted, as well as many thoroughly practical advantages are successfully achieved.

As many possible embodiments may be made of the above invention, and as many changes might be made in the embodiment above set forth, it is to be understood that all matter hereinbefore set forth or shown in the accompanying drawing is to be interpreted as illustrative and not in a limiting sense.

I claim:

1. In apparatus of the character described, in combination, an X-ray tube, a pair of condensers serially connected and adapted to be bridged across the terminals of said X-ray tubes, means for alternately charging said condensers, said means comprising a source of alternating relatively high potential and uni-directional valve means, and synchronously operated mechanism for successively connecting serially said source of high potential, one of said condensers, and said valve means and then said source of high potential, said valve means, and the other condenser.

2. In apparatus of the character described, in combination, a pair of condensers and means for uni-laterally and successively charging said condensers, said means including a source of alternating relatively high potential, uni-lateral valve means, and synchronously driven means adapted to effect a periodic connection serially of one condenser, said source of high potential, and said valve means, and adapted to change the constants of the circuit of the other condenser, thereby to prevent the full cumulative potential of said source and of said other condenser from being impressed upon said valve means.

3. In apparatus of the character described, in combination, a pair of condensers and means for uni-directionally and successively charging said condensers, said means including a source of alternating relatively high potential, uni-lateral valve means, and synchronously driven circuit controlling means adapted to effect a periodic connection serially of one condenser, said source of high potential, and said valve means, and to interpose in the circuit of the other condenser and said source of high potential a gap, said gap being proportioned to prevent said valve means from being subjected to the full cumulative potential of said source of high potential and of said other condenser.

4. In apparatus of the character described, in combination, a condenser arranged se-

rially with a source of alternating relatively high potential, a uni-lateral valve, and a gap formed of two spaced electrodes, and means synchronously effective for substantially closing said gap, said gap electrodes being shaped and spaced to have a capacity equal to or less than the capacity of said valve.

5. In apparatus of the character described, in combination, an X-ray tube, means including a source of alternating relatively high potential for supplying energy to said X-ray tube, and a synchronously driven switch for periodically permitting the flow of high tension energy from said source, said switch having a fixed terminal and a coacting rotatable circuit controlling member, the latter comprising a main body portion and a projecting blade-like member of stream-line cross-section, said fixed terminal and said main body portion of said rotatable member being shaped to present surfaces of relatively large radii of curvature.

6. In apparatus of the character described, in combination, an X-ray tube, a condenser for supplying energy to said X-ray tube, a source of relatively high alternating potential for charging said condenser, a uni-lateral valve in the charging circuit of said condenser, a synchronously operated mechanism for closing said charging circuit of said condenser at alternations of one polarity of said source, said mechanism including means effective at alternations of other polarity for interposing in the circuit of said valve a potential drop of such an order that the valve is safeguarded against the combined potentials of said charged condenser and of said last-mentioned alternations.

7. In apparatus of the character described, in combination, an X-ray tube, a condenser for supplying energy to said X-ray tube, a source of relatively high alternating potential for charging said condenser, a uni-lateral valve in the charging circuit of said condenser, a synchronously operated switch for closing said charging circuit of said condenser at alternations of one polarity of said source, said switch having a capacitance, when in circuit-opening position of such a value that the potential drop therein is sufficient to safeguard the valve against the combined potentials of said charged condenser and of said last-mentioned alternations.

8. In apparatus of the character described, in combination, a pair of condensers and means for uni-laterally and successively charging said condensers, said means including a source of alternating relatively high potential, uni-lateral valve means, and synchronously driven mechanism adapted periodically to effect a connection serially of one condenser, said source of high potential, and said valve means, said mechanism including means effective to interpose between

said valve means on the one hand and said source and other condenser on the other hand a capacitance of such a value that the valve means are safeguarded against the cumulative potentials of said source and said other condenser.

9. In apparatus of the character described, in combination, a pair of condensers; and means for uni-laterally and successively charging said condensers, said means including a source of alternating potential, a uni-lateral valve, and synchronously operated means adapted at a half-wave of one sign of said alternating potential to effect a serial charging connection of said source, one of said condensers, and said valve and at a half-wave of opposite sign to reverse the relation of said valve in its serial connection.

10. In apparatus of the character described, in combination, an X-ray tube, a source of alternating potential of a magnitude substantially half of that appropriate for operating said X-ray tube, means for energizing said X-ray tube comprising two condensers connected in series, a uni-lateral valve, and means synchronously operative for connecting in series said source of potential, one of said condensers, and said valve and then said source of potential, the other condenser, and said valve.

11. In apparatus of the character described, in combination, an X-ray tube, a source of alternating potential of a magnitude substantially half of that appropriate for operating said X-ray tube, means for energizing said X-ray tube comprising two condensers connected in series, a uni-lateral valve, and synchronously operative means adapted at a half-wave of one sign to close a series circuit comprising said source, one of said condensers, and said valve and to effect a series circuit including said source, the other of said condensers, said valve and a capacitance of a value sufficient to safeguard said valve in said last-named circuit against the cumulative potentials of said source and said last-mentioned condenser, and at a half-wave of opposite sign to close a series circuit including said source, the other of said condensers and said valve and to effect a series circuit including said source, said first-mentioned condenser, said valve, and a capacitance of a value sufficient to safeguard said valve in said last-mentioned circuit against the cumulative potentials of said source and said first-mentioned condenser.

12. In apparatus of the character described, in combination, two condensers, a

source of alternating potential, a uni-lateral valve, means connecting said condensers and said source for charging the condensers from said source so that one condenser and said source form part of a series charging circuit and the other condenser and said source form part of a second series charging circuit, and synchronously operative means for inserting said valve first in one series circuit and then in the other.

13. In apparatus of the character described, in combination, two condensers, a source of alternating potential, a uni-lateral valve, means connecting said condensers and said source so that one condenser and said source form part of a series circuit and the other condenser and said source form part of a second series circuit, means forming a capacitance, and synchronously operative means for first inserting said valve in one series circuit and said capacitance means in the other and then inserting said valve in the other series circuit and said capacitance means in said first-mentioned circuit, whereby said valve, when, effective in one circuit, is safeguarded against the cumulative potentials of said source and of the condenser in the other circuit.

14. In apparatus of the character described, in combination, a condenser, a source of alternating potential for charging said condenser, a uni-lateral valve connected so that said condenser is charged from said source at half waves of the latter of one sign, and means effective during half waves of the other sign for preventing the impression across said valve of the full cumulative effect of the potential of the charging condenser and the potential of the half wave of said other sign.

15. In apparatus of the character described, in combination, a condenser, a source of alternating potential for charging said condenser, a uni-lateral valve connected so that said condenser is charged from said source at half waves of the latter of one sign, and means effective at half waves of the other sign for changing the constants of the circuit of said valve and for thereby causing a potential drop in the said circuit of such an order that the valve is safeguarded against the combined potentials of the charged condenser and of the suppressed half wave of said source.

In testimony whereof, I have signed my name to this specification this 4th day of December, 1926.

FRANKLIN S. SMITH.
